FOOD SERVICE TRAY

John A. Bridges and Harold W. Storrs, Nashville, Tenn.,
assignors to Aladdin Industries, Incorporated, Chicago,
Ill., a corporation of Delaware

Filed Nov. 13, 1969, Ser. No. 20,059

Term of patent 14 years

Int. Cl. D7—99

U.S. Cl. D44—10

FIG. 1 is a top perspective view of a food service tray showing our new design;

FIG. 2 is a view taken along the line 2—2 of FIG. 1;

FIG. 3 is a side view taken along the line 3—3 of FIG. 1;

FIG. 4 is a view taken along the line 4—4 of FIG. 1;

FIG. 5 is a side view taken along the line 5—5 of FIG. 1;

FIG. 6 is a bottom view taken along the line 6—6 of FIG. 4;

FIG. 7 is a sectional view taken on line 7—7 of FIG. 1 on an enlarged scale;

FIG. 8 is a sectional view taken on line 8—8 of FIG. 1 on an enlarged scale;

FIG. 9 is a sectional view taken on line 9—9 of FIG. 1 on an enlarged scale;

FIG. 10 is a sectional view taken on line 10—10 of FIG. 1 on an enlarged scale; and

FIG. 11 is a sectional view taken on line 11—11 of FIG. 1 on an enlarged scale.

We claim:

The ornamental design for a food service tray, as shown.
